UNITED STATES PATENT OFFICE.

PETER C. ENNS, OF HERBERT, SASKATCHEWAN, CANADA.

AUTOMATIC SIGNAL.

Application filed November 8, 1923, Serial No. 673,498, and in Canada March 31, 1923.

The present invention relates to automatic signals and particularly appertains to that class of device which is audible.

A further object of my invention is the provision of such a device that is train controlled.

A further object of my invention is the provision of such a device that is carried by a railway train and is thrown into operation by a depending member striking against or engaging with some ground member or stop positioned on the track.

A still further object of my invention is the provision of such a device wherein a specified signal may be produced at any desired place by the train passing a stop located thereat.

With these and other objects in view my invention resides in the construction, combination and arrangement of the cooperating parts as shall be hereinafter more fully described, illustrated in the accompanying drawings and pointed out in the claims hereunto appended. In the drawings wherein like characters of reference designate like parts throughout the several views,

Figure 1 is an elevation of a truck showing the preferred embodiment of my device,

Figure 2 is a longitudinal section of the truck shown in Figure 1,

Figure 3 is an enlarged detailed elevation showing a portion of the same truck in dotted form and illustrating the signal device in definite outline,

Figure 4 is a plan of a fragment of railway track with the stop device in position,

Figure 5 is a perspective of railway track with the stop device in position,

Figure 6 is an enlarged perspective of the stop device,

Figure 7 is a detail of the trigger,

Figure 8 is a detail of the device designed to reset the clutch controlled shaft,

Figure 9 is a detail of the roller-carrying socket that engages with the whistle-actuating cam,

Figure 10 is an elevation of the clutch and cam mounted on the shaft,

Figure 11 is a vertical section of the clutch,

Figure 12 is a side elevation of the male portion of the clutch,

Figure 13 is a side elevation of the female portion of the clutch, and

Figure 14 is a side elevation of the cam.

In the drawings, the numeral 15 designates the trigger and the numeral 16 the trip or stop. This trigger 15 hangs from the truck 17 and when the said truck passes over that part of the track 18 alongside of which the trip 16 is arranged, the said trigger 15 engages with the trip 16. This trigger 15, as illustrated in Figure 7, is provided with means 19 to allow it to yield when acted on from the reverse side, so that the trigger will not cause operation of the signal when the train "backs up," but only when the said trigger 15 engages with the trip 16 when the train is advancing.

The shaft 15' of the trigger 15 is journaled beneath the truck, as at 16', and has an inturned crank portion 17' adapted to normally engage and hold the spring controlled lever 20 inoperative. When the trigger is tripped by the trip 16, the crank portion 17' is moved from engagement with the lever 20. This lever 20 is positioned in the male portion 21 of the clutch denoted in general by the numeral 20', which, due to the eccentric location of its pivot-pin 22 and the tension of the coil spring 19', moves radially outward from the centre of the clutch 21 so that the stud 23, positioned proximate to the outer end of the said lever 20, engages with the scallops or recesses 18' arranged about the inside of the periphery of the flange 22' of the disk 24, forming the female portion of the clutch.

The engaging clutch members 21 and 24, together with the cam 25, are mounted on the shaft 26; the male member 21 of the clutch and the cam are keyed to the said shaft 26 as at 50 and 51 while the female portion 24 of the clutch, provided with collars 52, rides free thereon. Keyed to an axle of the truck 17 is the large gear wheel 27, that is adapted to mesh with or otherwise actuate the female clutch member 24, the outer rim of which is provided with gear teeth 53.

As will be obvious, when the train is in motion the gear 27 rotates the clutch member 24; when the trigger 15 is tripped by the stop 16, that horizontal crank portion 17' that holds the lever 20 inactive, is moved out of engagement with the said lever, the end of which is thrown outwardly, causing the engagement of the clutch and the forced motion of the male clutch member 21, keyed to the shaft 26, rotates the cam 25 and

thereby operates mechanism 28 that controls the valve 29 conveniently positioned in the air or steam line 30.

It is desired that the gearing 31, if such be deemed necessary intermediate the gear wheel 27 and the clutch member 24 may be such as will properly time or regulate the rotation of the shaft 26 to allow of the cam 25 producing the required signal.

10 This cam, as designed and shown in Figure 14, is intended to cause a certain timing of the mechanism 28 to operate the control valve 29 to produce the conventional "cross X—X road signal" and it is obvious that, if 15 the mechanism 28 connecting the valve 29 with the operation of the cam 25, is set to be normally seated as at 32, intermediate a large and small eminence or extension 54, and the cam 25 turns in the direction, as indicated by the arrow to bring the large extension into prior engagement, the rising and falling of the roller-carrying socket 33, adapted to ride the circumference of this cam, will actuate the member 28 to operate 20 the pipe valve to produce a specific audible signal. If the desired signal be two long and two short emissions, a suitable cam may be 25 designed to produce such.

After striking the stop 16 and so causing 30 engagement with the clutch mechanism it is preferred that besides the power of gravity, some auxiliary agent, such as spring 14 or the like, be employed to bring the trigger 15 back to rest in its normal hanging position as soon as possible, so that the horizontal crank portion 17', that engages with the lever 20, may be bearing against the circumference 34 of the male clutch member 21 by the time the said clutch member has described 35 three quarters of a revolution; the object of this is to permit of the immediate disengagement of the stud 23 from the recesses 18' of the disk 24 or female portion of the clutch, on the completion of a revolution, and consequently of the male clutch member and the 40 shaft 26 to which it is keyed. The release, and coming to rest, of the shaft 26 and also of the cam 25, is attended by the operation of the reset device 35, as shown in Figure 8, which is adapted to govern the rotative position of the shaft 26 so that the hollow or 45 depression 32 of the cam may be normally carrying the socket roller 33 and so be properly set for the ensuing operations. This reset device 35 is mounted on an end of the shaft 26 and includes a coil spring 36 pivotally carried by an eccentrically positioned pin 37. This spring 36 is connected to some suitable part of the truck 17.

50 The preferred form of stop 16, as illustrated in Figure 6, comprises a pair of longitudinal strips 38 to the ends of which are connected the four upwardly-extending, arcuate supports 39. The upper flanges of these supports carry the beam 40. Pivotally

connected to this beam, intermediate the braces 39, are the coacting levers 41 and 42, which constitute the stop proper, the opposite ends of which levers are pivotally joined by the connecting strip 43. Running longitudinally of and below the beam 40 are the rods 44, having their inner ends pivotally connected, as at 45 to the lower ends of the levers 41 and 42, and their opposite ends 55 slidably mounted in the sleeve brackets 46, positioned on the uprights 46' that rise at each end from the base members 47, and coiled about these rods are the tension springs 48 secured to the uprights 46 at their outer ends and the connections 45 at their inner ends.

This construction is designed to lend a cushion effect to the striking of the depending trigger 15 and to minimize the resulting 60 jar.

In the event of this device being employed as a "cross-road", or similar signalling means, or where it be considered advisable to provide some automatically operated device, to allow of the exoneration of the train operator, in case of collisions or accidents, it is desired that it be so constructed that access to disassembly or its rendering inoperative may be through a minimum of entrances and that all such accessible points 65 be provided with some conventional means for sealing as shown at 50 in Figures 4 and 6. While it will appear, from the fact that the operation is through the medium of an air or steam line 30, that my preferred 70 form of signal is a whistle, it is understood that the mechanism 28 may bring into actuation any suitable form of audible signal.

From the foregoing description taken in connection with the accompanying drawings it will be obvious that an automatic, 75 audible signal is provided which will fulfill all the necessary requirements of such a device, and it should be understood in this connection that various minor changes in the detail of construction may be resorted to, within the scope of the appended claims, 80 without departing from the spirit, or sacrificing any of the advantages of the invention.

115 What I claim is,—

1. An automatic signal controlling mechanism, including a main shaft, a clutch comprising male and female members; the former of which is keyed to said shaft while the latter rides free thereon, said female member having an interiorly notched flange, a spring-tensioned lever eccentrically pivoted to said male member, said lever having a laterally projecting stud at its outer end, 120 adapted to engage the notches of said flange to establish connection between the male and female members, a driving gear adapted to rotate said female member, a second shaft disposed adjacent said main shaft having a 125

trigger at one end, a crank formed in said second shaft adapted to engage and normally hold said lever in an inoperative position, a trip for actuating said trigger, a cam keyed on said main shaft, and signal operating means actuated by said cam.

2. An automatic signal controlling mechanism, including a main shaft, a female clutch member mounted to ride free on said shaft, driving means for said female clutch member, a male clutch member keyed on

said shaft having means for inter-engagement with said female clutch member, a second shaft having a crank portion adapted to normally hold said clutch members out of engagement, a trigger associated with one end of said second shaft, a trip for actuating said trigger, a cam keyed on said main shaft, and signal operating means actuated by said cam.

In testimony whereof I affix my signature.

PETER C. ENNS.
